UNITED STATES PATENT OFFICE.

GIUSEPPE RANUCCI, OF NEW YORK, N. Y.

DESIGN FOR MACARONI OR SIMILAR ARTICLE.

Application filed January 17, 1925. Serial No. 12,076. Term of patent 14 years.

To all whom it may concern:

Be it known that I, GIUSEPPE RANUCCI, a subject of the King of Italy, and a resident of the city of New York, in the borough of Manhattan, county of New York, and State of New York, have invented a new, original, and ornamental Design for Macaroni or Similar Article, of which the following is a specification, reference being had to the accompanying drawing, forming part thereof.

Fig. 2 is a side view thereof, and

Fig. 3 is a perspective view.

I claim:

The ornamental design for macaroni or similar article, as shown.

GIUSEPPE RANUCCI.
